UNITED STATES PATENT OFFICE.

LESLIE A. VANDIVER, OF CHICAGO, ILLINOIS, ASSIGNOR TO STAR NOVELTY MANUFACTURING CO., OF SHELBINA, MISSOURI.

VENDING-MACHINE.

1,113,919.

Specification of Letters Patent. Patented Oct. 13, 1914.

Application filed September 22, 1913. Serial No. 791,229.

To all whom it may concern:

Be it known that I, LESLIE A. VANDIVER, a citizen of the United States, residing at Chicago, in the county of Cook and State of Illinois, have invented a new and useful 5 Vending-Machine, of which the following is a specification.

This invention relates to vending machines of that type disclosed in Patent No. 10 1,012,940, issued to me on December 26, 1911.

One of the objects of the invention is to provide improved means for use in connection with a conveying arm, whereby boxes or packages of merchandise can be securely 15 engaged, elevated, and then conveyed to the point of delivery.

A further object is to provide a novel arrangement of package engaging needles designed, when released, to project into the 20 package or box along downwardly diverging lines so that, as long as these needles are in projected or active positions, they will be incapable of withdrawal from the engaged package until retracted by means provided 25 for that purpose, thus insuring the elevation of the engaged package when the picking up and conveying mechanism is operated.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed, can be made within the scope of what is claimed, without departing from the spirit of the invention.

In the accompanying drawings the preferred form of the invention has been shown.

In said drawings: Figure 1 is a side elevation of the picking up mechanism constituting the present invention. Fig. 2 is a vertical section through the needle controlling mechanism, said needles being shown projected into engagement with a package a portion of which is shown in section. Fig. 3 is a section through the lower portion of the mechanism and showing the needles retracted out of engaging position.

Referring to the figures by characters of reference 1 designates a portion of a tubular standard within which a stem 2, a portion of which has been illustrated in Fig. 1, is 55 adapted to slide. Standard 1 has a slot 3

and extending through this slot is an arm 4 which is fixedly attached to the stem 2 so as to slide therewith. Another arm 5 is arranged above arm 4 and has a depending guide rod 6. Arm 4 is provided with a yoke 7 at its free end and in this yoke is secured a tubular spindle 8 adapted to slide on the arm 4. A sleeve 9 is slidably mounted on the spindle 8 and a spring 10 is housed in the sleeve and bears at one end against an enlarged portion 12 of the spindle and at its other end upon an interior flange 13 formed in the sleeve. The sleeve 9 has a head 14 at its upper end provided with an annular shoulder 15. This shoulder is adapted, 70 when the sleeve is raised, to be engaged by a lip 17 extending from a locking lever 18 which is pivotally connected to arm 4 and is held normally in engaging position by a spring 19.

The parts above described do not constitute in themselves, any part of the present invention but have already been disclosed in co-pending applications filed by me and of even date herewith.

The lever 18 has a slot 20 through which extends a supporting plate 21 secured to the lower end of yoke 7. A spindle 22 is secured at its upper end to this plate 21, as by threading the upper end of the spindle 85 to form a nipple 23 projecting through plate 21 and engaged by a nut 24. The two spindles 8 and 22 extend downwardly the same distances from the plate 21 and are fixed relative to each other and to the plate 90 21. Spindle 22 has a sleeve 25 slidably mounted thereon and this sleeve is of the same length as sleeve 9 and is connected thereto at an intermediate point, by a block 26, whereby the sleeves are maintained parallel. A spring 27 similar to the spring 11 is housed in sleeve 25 and bears at one end against an enlargement 28 on the spindle 22 and at its other end against an interior flange 29 formed within the sleeve 25. Thus 100 the two springs 11 and 27 serve to hold the sleeves 9 and 25 normally pressed downwardly until an actuating plate 30, which rotates on the upper end portion of sleeve 9, comes into contact with the lip 17 as shown 105 in Fig. 1. This actuating plate 30 does not constitute any part of the present invention but has already been disclosed in detail in one of my co-pending applications herein referred to.

Embracing and pivotally connected to the lower end of each spindle 8 and 22 is a yoke 31 having a needle 32 extending therefrom. The yokes are adapted to swing about parallel axes and the needles 32 are slidably mounted within downwardly diverging openings 33 formed in the bottom of a foot or thimble 34. This thimble is made up of parallel sleeves 35 connected by a web 36. 10 A block 37 connects the sleeves 9 and 25 close to the thimble 34 and has a holding spring 38 extending therefrom and adapted to engage the web 36, and thus lock or secure the thimble upon the ends of the sleeves 9 and 15 25. It will be seen that, under normal conditions, the shoulder 15 is out of engagement with lip 17 and, consequently, the springs 11 and 27 hold sleeves 9 and 25 in their lowermost positions, with the plate 30 20 bearing on lip 17, as shown in Fig. 1, and the points of the needles 32 seated in the diverging openings 33.

When the mechanism constituting this invention is moved against a package, box or 25 other article to be dispensed, the thimble 34 first comes into contact with said package or box and, as the apparatus continues in its movement toward the said package or box, the spindles 8 and 22 will push against the 30 yokes 31 and cause the needles 32 to slide outwardly along diverging lines and into the bundle or box, as shown in Fig. 2. During this movement the springs 11 and 27 will be placed under compression and, upon 35 the completion of such movement, the shoulder 15 will come into engagement with lip 17, thus locking the sleeves 9 and 25 in the positions shown in Fig. 2 and with the needles 32 projected outwardly along diverging lines and into the engaged package. Consequently, when the apparatus is elevated, the needles 32 cannot withdraw upwardly from the engaged article and, as a 40 result, this article will necessarily be elevated with the apparatus and, by swinging arm 4 laterally, the said adhering article can thus be conveyed to the point of discharge. By means of plate 30, the locking lever 18 can be shifted so as to disengage lip 17 45 from shoulder 15 whereupon the tensioned springs 11 and 27 will shift the sleeves 9 and 25 downwardly along the spindles 8 and 22. Consequently the thimble 34 will slide along the needles 32 and strip the article 50 from them so that said article will be freed from the apparatus.

In order that an article such as a box or the like will be prevented from sagging, while in engagement with the apparatus, a 55 steady shoe is preferably used in connection therewith. As shown in Fig. 1, a rod 39 may be extended downwardly from arm 5 and provided, at its lower end, with a ring 40 adapted to extend around the sleeves 9 and 25. Rod 39 is so proportioned that,

when the box is elevated to its uppermost position by the outwardly projecting and downwardly diverging needles 32, it will be brought into contact with the ring 40 or else close to the ring so that objectionable sagging of the bundle, if supported at a point off center, is prevented. 70

It has been found in practice that engaging means such as herein described is particularly desirable for use in connection with boxes of candy, and like articles, packages of chewing gum and, in fact, wherever it is desired to dispense packages of different sizes and kinds. 75

What is claimed is:—

1. In a vending machine, article engaging means including parallel spindles, means for shifting the spindles toward an article to be engaged, a needle pivotally connected to each spindle, a thimble shiftable relative to the spindles and having downwardly diverging apertures for the reception of the respective needles, and yielding means for holding the thimble normally in position to house the points of the needles. 80

2. In a vending machine, article engaging means including needles adapted to swing about parallel axes, means for pressing the needles against an article to be engaged, and a thimble movable against and adapted to be stopped by said article to be engaged, the said thimble being movable relative to and engaging the needles for spreading apart the points of the needles while entering an object. 90

3. In a vending machine, article engaging means including a thimble movable against and adapted to be stopped by said article, needles slidably mounted in the thimble and adapted to swing about parallel axes, means for projecting the needles through and beyond the end of the thimble and into engagement with the article engaged by the thimble, said thimble constituting means for swinging the needles apart during such movement. 105

4. In a vending machine, article engaging means including a thimble, needles slidably mounted in the thimble and adapted to swing about parallel axes, means for projecting the needles through the thimble and into engagement with an article engaged by the thimble, said thimble constituting means for swinging the needles apart during such movement, and means adapted to be placed under compression by such movement of the needles relative to the thimble, for pressing the thimble yieldingly against the engaged object. 115

5. In a vending machine, the combination with parallel sleeves, a thimble connected to the free ends thereof, and means for detachably securing the thimble to the sleeves, of a spindle within each sleeve, means upon the spindles for holding the sleeves nor- 120 125 130

- mally projected beyond one end of the spindles, needles pivotally connected to the respective spindles and having their points normally protected by the thimble, and
- 5 means for directing the thimble and needles toward an object to be engaged, said thimble constituting means for swinging the needles apart while entering the object engaged by the thimble.
- 10 6. In a vending machine, a thimble for movement against an article to be engaged, needles normally housed in the thimble, and means for projecting the needles beyond the end of the thimble and into the article contacted by said thimble, the said thimble constituting means for directing the needles along lines diverging into the article.
- 15 7. In a vending machine, article engaging means including spaced needles, means for directing the needles into an object to be conveyed, means coöperating with the needles for swinging them apart while entering the engaged object, and means for automatically securing the needles against movement toward each other.
- 20 8. In a vending machine, article engaging means including needles mounted to swing toward and from each other, means for directing the needles into an article to be engaged, yieldable means for engagement with said article for swinging the needles apart while entering the article, and means for securing said last named means automatically against return movement to fasten the
- 25 needles in spread position.
- 30 9. In a vending machine, article engaging
- means including pivotally mounted needles, means for projecting them against and into an article to be conveyed, a thimble adapted to bear against the engaged article and to spread the needles apart while entering the article, means for holding said thimble yieldingly against the engaged article, means for locking the thimble against movement relative to the needles to hold the needles spread apart in engaging position, and means for releasing the thimble.
- 35 10. In a vending machine, separate pivotally mounted article engaging needles, means for directing the needles into engagement with an article to be conveyed, means movable against said article for swinging the needles apart while in engagement with said article, means for securing the needles in spread position, and means movable toward and from the article with the needles for holding the article against swinging movement on the needles.
- 40 11. In a vending machine, an article engaging needle, means for shifting the same into engagement with an article, and a foot adjacent the needle for bearing against the engaged article to hold it against swinging movement relative to the needle.
- 45 12. In testimony that I claim the foregoing as my own, I have hereto affixed my signature in the presence of two witnesses.
- 50 13. LESLIE A. VANDIVER.
- 55 Witnesses:
N. P. BISHOFF,
ROBERT COWLES.
